DESIGN FOR A COOLER CABINET OR THE LIKE

Simon J. Lonergan, Albion, Mich., assignor to Lonergan Manufacturing Company, Albion,
Mich., a corporation of Michigan

Application January 10, 1945, Serial No. 117,366

Term of patent 14 years

(Cl. D67—4)

To all whom it may concern:

Be it known that I, Simon J. Lonergan, a citizen of the United States, residing at Albion, in the county of Calhoun and State of Michigan, have invented a new, original, and ornamental Design for a Cooler Cabinet or the like, of which the following is a specification, reference being had to the accompanying drawing forming a part thereof.

In the drawing,

Fig. 2 is a top plan view of the cooler cabinet; and

Fig. 3 is a perspective view on a reduced scale of the rear of the cooler cabinet.

I claim:

The ornamental design for a cooler cabinet or the like, substantially as shown.

SIMON J. LONERGAN.
